FOOTBALL GAME

Clifford D. Keely, Bloomfield, and Otto H. Schwanemann, Jr., Newark, N. J.; said Schwanemann assignor to George Bartels, Jr., Teaneck, N. J.

Application December 23, 1937, Serial No. 181,260

3 Claims. (Cl. 273—94)

Our present invention relates to an improved table football game involving both elements of skill and chance. In our improved game a representation of a football is moved upon a field simulating an actual football playing field. After the ball has been put in play in a manner to be described, the player having the ball is enabled to choose a play from several possible plays which in his opinion will best be calculated to advance the ball. At the same time the second or defensive player chooses one of a number of possible defensive plays which will most nearly anticipate the play of the first player, and to the extent that he does anticipate the play, the first player fails to advance the ball. In order to put the ball into play and determine its position prior to the first down, we preferably provide one or more devices of chance, as for instance a dial and spinner, by means of which to determine the position of the ball following the kick-off and also the run-back immediately following. Further use is made of such device or devices in subsequent open plays, i. e., in the case of kicks, passes, etc., as will be described hereinafter.

According to our preferred embodiment, each one of a plurality of offensive plays may be answered by any one of a plurality of defensive plays, the results of selected plays being arranged in ranks and files, e. g., the results of the offensive plays being arranged in files, whereas the results of the defensive plays are arranged in ranks, or vice versa. Each rank and each file of play-results has associated with it indicia, or legends giving the types of play which are to be used by the player for making his selection. Means are then provided whereby the players, having chosen their respective plays, are enabled to view the result of the one as modified by the other, which result is to be found at the particular rank with the particular file involved. Further in accordance with our preferred embodiment, the defense indicia are the same as the offense, the arrangement being such that the defensive player makes the best play when he anticipates the exact play of the offense. Moreover, to the extent that he approximates the exact play, to such extent does he check the offensive player.

Our invention will be best understood by reference to the following detailed description taken with the annexed drawings in which:

Fig. 1 is a view in perspective of our improved game with the cover closed.

Fig. 2 is an enlarged view in plan of the cover showing the dials used thereon.

Fig. 3 is an enlarged view of the chart containing the results of play together with the indicia constituting the schedule of plays both for the offense and defense.

Fig. 4 is a view seen from the right of Fig. 1 and showing an improved swivel mounting for the chart.

Fig. 5 is a perspective view of a representation of a football field.

As best seen in Fig. 3, 10 denotes the board upon which is printed or engraved preferably duplicate rows 11 constituting the schedule of offensive plays, for convenience the lower row 15 11 being printed upside down from the upper row or vice versa, thus permitting the printing to be easily read by the player sitting opposite so that he may become acquainted with the strategy of the offensive player. Similar rows 12 20 containing preferably the same legends or indicia are likewise provided for the second or defensive player. For each offensive play (the plays being numbered 1 to 16 as shown, although more or less may be employed) there is likewise 25 a column of results, such columns or files containing preferably the same number of squares as there are plays, although this is not essential, as the number of squares per column may be either less or more. It will also be noted that the 30 squares in the vertical columns are also arranged in rows or ranks opposite the schedule of plays 12 for the defensive player so that the result of a play by the offensive player will be determined by the intersection of the vertical column or 35 file chosen by the offensive player, with the horizontal row or rank determined by the defensive player.

Fig. 3 illustrates a preferred arrangement for indicating the results of the plays chosen by the offensive and defensive players. Here a slot 15 is provided for the defensive player in which is movable a slider 17 to which is attached a loop 18 preferably of wire and of a size and shape to cover one complete rank of squares. Similarly 45 a slider 19 having a loop 20 and movable in a slot 21 is provided for the offensive player. Preferably the board 10 is pivotally mounted upon a base 22, having legs 21, by means of a swivel or pivot 23, whereby when the ball changes 50 hands the board can be turned 180° so that the player who was playing the defensive side on the board now plays the offensive side.

It is desirable that the ranks and files of results of plays on the board 10 are concealed from 55

the players during the time that the offensive and defensive plays are being chosen. A preferred means for accomplishing this is in the form of a cover 25 which is spaced slightly from the board 10 by a bead 26 at one side and feet 27 at the opposite side in order to accommodate the loops 18 and 20, the cover being hinged as by means of a fabric 28 of suitable material glued to the cover 25 and the bead 26 or by other means.

10 As previously indicated, certain situations in the game are determined by chance, and one convenient means providing for this are dials 30, 31, 32, 33. To economize space, dials 30 and 31 may be arranged concentrically as are dials 32 15 and 33. Each dial has a compound spinner 34 and 35, respectively, each spinner having two pointers as shown, one for the inner dial and one for the outer dial. Desirably concentric dials and the respective pointers therefor are provided 20 with distinctive colors. Conveniently these dials are mounted upon the cover 25 which also may contain dials 36, 37 with pointers indicating the number of downs and quarters, respectively. The dials are labelled in the drawings, dial 30 being 25 termed "Receive kick," dial 31, "Run of pass," dial 32, "Field goal," and dial 33, "Kick-off" or punt.

Fig. 5 shows at 40 a representation of the football field, whereas 41 shows the representation of 30 the football. The plan of field 40 differs from that of an actual field only in that lateral zones are provided by longitudinally extending lines 42. The use to which such zones are put will be apparent from the illustrative plays about to be 35 described. Illustrative plays of the game in which each player in effect plays the role of quarter back and utilizes the field 40 and ball 41 in the first described form of the game are as follows, the usual football rules being employed 40 where applicable.

To start the game, it is determined by lot 45 which player shall have the decision to kick off or receive. Assuming it is player A, and he chooses to kick, he spins the pointer on the dial marked "Kick-off" and the result is indicated by the end of the pointer arm, reading upon the inner circle 33. In the assumed play, the pointer stops at the segment of the inner circle marked "35 yards 2 zones left." The ball is thereupon 50 advanced from the usual kick-off position, i. e., A's 40-yard line, a distance of 35 yards, and 2 zones to A's left of the center zone and there located. Zones are indicated by the lines running parallel in the length of the field. Left or 55 right is decided by facing in the direction the ball is travelling at the time. Player B, now the defense, spins the pointer on dial No. 30 marked "Receive kick," the assumed indicated result being that the ball is run back 30 yards, 2 zones 60 to B's left, thus placing the ball in the center lateral zone and upon B's own 45 yard line. The ball is in the center zone again, because the direction of travel has been reversed and therefore left and right on the return is also reversed.

65 B is now the offense, his first down with the usual 10 yards to go. B is now the offensive player and the game board is now turned until the side reading offense is in front of B, who will now use the corresponding play selector, 70 while A, now the defensive player, will use the defensive play selector. A spacer element, not shown, denoting 10 yards is placed at the position of the ball and in the direction of A's goal. B, influenced partly by the position of the ball on 75 the field also possibly aiming to outwit A, men-

tally selects one of the several possible plays he believes will result in best advancing the ball, while at the same time A mentally selects a play which he believes will most closely anticipate B and if thereby prepared for B's offense, hence nullify B's play and possibly cause a loss of 5 yardage to B.

When both players have indicated "ready," together they move the sliders 18 and 20 to bring them opposite the plays decided on by them. 10 For example, B moves slider 20 to play numbered 5, denoted "left tackle," while A moves to play numbered 2. By raising the dial board the result of the two selected plays is read in the square determined by the intersection of the two 15 sliders. In the plays given, this result is 3 yards gain for B. The ball is thereupon moved 3 yards forward, and, since it is a left tackle play, one zone to B's left. Should the result have been "no gain," the ball would still have been moved 20 one zone left. It is now second down with 7 yards to go, whereupon A and B again choose their respective offensive and defensive plays. This time B chooses play No. 9, "forward pass 25 right," while A chooses play No. 4, "right end sweep." The result is read as: "15 yard toss 30 intercepted; play 6 or 7." The ball thereupon is moved forward 15 yards, and since the play was a forward pass right, one zone to the right. Now, to determine if the player intercepting the 35 ball is "in the open" or tackled at the point of interception, A and B move their respective pointers to plays 6 or 7. The net result of B's choice of either play 6 or 7 and A's choice of either 6 or 7 determines now the result. Assuming B moved to 7 while A moved to 6, the result is read as "in the open," such designation pertaining to this type of play only. A now spins the dial 30 marked "Run or pass" and the result is, for example, an 18 yard run-back one zone 40 right (inner circle). A now assumes the offense and the board is turned 180° to permit A to work the offensive slider. The ball thus continues in play until an agreed time period is up, the scoring being the same as in the ordinary football game. 45

If desired, suitable means, not shown, may be employed for anchoring the ball in any position on the field as by providing the same with a pin and having a board of suitable material to receive same, or other means may be employed 50 known to the art. It will also be understood that other devices for determining the initial position of the ball following the kick-off and for other open plays may be used in combination with the play selectors shown in which the result of an 55 offensive play as affected by the defensive play is determined. In further reference to said play selectors it will be noted that the defensive play indicia are the same as the offensive play indicia, thus making the game easy to learn and to play, 60 although the same principle of our invention may be employed by having the defensive indicia different from the offensive.

In the claims the terms "rank" and "file" are 65 used in a relative sense to mean that one row of results is crosswise to the other, without regard to their absolute position in space, i. e., whether vertical or horizontal.

It will be understood that various changes may be made in the above described specific embodiment of our invention without departing from the spirit thereof or the scope of the appended 70 claims.

We claim:

1. In a football game of the type having a rep- 75

resentation of a football field, and of a football movable upon said field, a chart containing the results of selected plays, said results being arranged in ranks and files, each of said files 5 terminating in an indicium denoting an offensive play, each of said ranks terminating in an indicium denoting a defensive play, an indicator movable to choose any one of said offensive indicia and extending across said ranks, an indicator movable to choose any one of said defensive indicia and extending across said files, the intersection of said indicators upon a given result being that of the offensive play as affected 10 by the defensive play, and a cover for said chart concealing in closed position said ranks and files 15 of results but permitting a view of said indicia by the respective players.

2. In a football game of the type having a representation of a football field and a representation of a football movable upon said field, a chart containing results of selected plays arranged in ranks and files together with means

for selecting any file of results by the offensive player, said means including indicia on said chart respectively associated with each of said files, and denoting offensive plays, means for selecting any rank of results by the defensive player simultaneously with said offensive player, said means last mentioned including indicia on said chart respectively associated with each of said ranks, and denoting defensive plays, the intersection of the selected file with the selected rank denoting 10 the offensive play as affected by the defensive play and determining the position of the ball upon the field, and means for concealing the results of plays constituting the ranks and files but not said indicia while selections are made by the 15 players.

3. The device according to claim 2, in which said last mentioned means consists of a removable cover.
